UNITED STATES PATENT OFFICE.

WILSON D. EDWARDS, OF TERRE HAUTE, INDIANA, ASSIGNOR TO TURNER BROTHERS' COMPANY, OF TERRE HAUTE, INDIANA.

DESIGN FOR A GLASS BOTTLE.

Application filed October 5, 1923. Serial No. 7,407. Term of patent 3½ years.

To all whom it may concern:

Be it known that I, WILSON D. EDWARDS, a citizen of the United States, residing at 2019 Crawford St., Terre Haute, in the county of Vigo and State of Indiana, have invented a new, original, and ornamental Design for Glass Bottles, of which the following is a specification, reference being had to the accompanying drawing, forming a part thereof.

The figure is a perspective view of a glass bottle showing my new design.

I claim:

The ornamental design for a glass bottle, as shown.

WILSON D. EDWARDS.
